UNITED STATES PATENT OFFICE.

UUNO E. TUOMI, OF DALLAS, TEXAS.

SASH-OPERATING MECHANISM.

Application filed August 7, 1926. Serial No. 127,865.

This invention relates to windows of the swinging sash type and it refers more particularly to certain improvements in the operating mechanism for the sashes, its principal object being to provide a mechanism of the character designated, which will be completely hidden from view, yet positive in its action.

A further object of the invention resides in the capability of the mechanism to provide for selective raising and lowering of the sashes, either individually, in pairs or collectively.

Still further, the invention proposes, by reason of the positive action of the sash operating mechanism to maintain locked position of the sashes, irrespective of their positions whether at extremes or intermediate such extremes.

With these principal objects in view, other objects and practical advantages of the invention, including its salient features of construction and arrangement of parts, will become apparent as the description proceeds, taken in connection with the accompanying drawings wherein—

Figure 1 represents a front elevational view of a window constructed according to the present invention.

Figure 2 is a side view thereof.

Figure 3 is likewise a side view in reduced scale, in which the middle window is shown as being open.

Figure 4 is a front elevational view of the window in section, illustrating the operating mechanism.

Figure 5 is a plan view on lines 5—5 of Figure 6.

Figure 6 represents a side elevational view in vertical cross-section on lines 6—6 of Figure 1.

Figure 7 is also a plan view on lines 7—7 of Figure 1.

Figures 8 and 9 are top and side views respectively of a movable sleeve constituting a part of the sash moving mechanism.

Figures 10 and 11 are respectively top and side views of a sleeve likewise constituting a part of the sash controlling mechanism.

Figures 12 and 13 represent different views of springs employed for normally controlling the latching elements.

Figures 14, 15 and 16 illustrate different

views of the lever employed for latching the windows against movement.

Figures 17 and 18 are side and top views respectively of one of the braces employed.

Figure 19 is a detail view of a part of the operating mechanism by which the upper sashes are selectively controlled from below, and

Figure 20 represents a fragmentary plan view of an upper corner of the window to show the relative positions of the operating arms.

In proceeding more in detail with the drawings, the side stiles 1 of the invention are each provided with stops 2, as particularly apparent in Figure 7, and as a precaution against possible entrance and accumulation of water in the compartments occupied by the operating mechanism, channels 3 are defined by the stops 2 down which the water may run, to be discharged at the downwardly pitched sill 4, as in Figure 6.

In order to form a conservative joint between the sashes 5, they will be seen in Figure 6 as being preferably stepped to snugly conform when in closed position, one with the other.

The sectional front elevation shown in Figure 4 discloses that a plurality of vertical screw threaded shafts 6 are arranged in compartments situated in opposing stiles 1, the ends of which, as a precaution against wear, are rotatably mounted in bosses 7 in the crown bar 8 and sill 9. On the lower end of each shaft 6 is affixed a beveled pinion 10, and a horizontal shaft 11, mounted in bearings 12 within the sill 9, carries a number of similar pinions 13 so arranged as to engage the pinions carried by the vertical shafts 6. At the approximate center of the horizontal shaft 11, a pinion 14 is mounted in a bearing 15 securely affixed to the inside of the sill 9, and has protruding outwardly a squared shaft 16, upon which an operating crank 17 may be conveniently applied to rotate the horizontal shaft 11, and consequently the vertical shafts 6, simultaneously. Observance to Figure 6 will disclose that the vertical shafts 6 are further held by brackets 18, a detail view of which is illustrated in Figures 17 and 18.

Each of the sashes 5 are equipped with an individual actuating lever assembly, consist-

ing of arms 19 on opposing sides of each sash and rigid with respect thereto, and having their free ends pivotally attached to collars 20, freely movable on the vertical shafts 6, see Figure 6. Further, a lever 21, pivoted to either side of the sash and to another collar 22, also freely movable on the vertical shaft 6, and intermediate the ends of the levers 21 is pivoted links 23, while the opposite ends thereof are pivotally attached to the brackets 18, previously mentioned, and stationary with respect to the window facing.

Figures 14 to 16 inclusive all illustrate a particular form of controlling latch 24, which forms an operative part of the collar 20 to which the first mentioned arm 19 is pivotally attached. Upon this latch depends the movement of its respective sash, and it is through the same that selective raising and lowering is accomplished, as will become apparent presently. It will be noted in the mentioned figures that a segment of threads 25 are formed integral with the top of the member which conform with the helix of the threads on the vertical shaft 6, and when urged forward on its pivot 26 to effect such engagement, the collars 20 will move on the shafts accordingly with the direction of rotation thereof.

Referring now particularly to the means by which selective actuation of the sashes 5 is accomplished. It will be observed in Figures 1, 2, 3 and 6, that the front facing of the windows are apertured said apertures being covered with an apertured plate 27, through which a plurality of switches protrude, and are conveniently accessible from the inside of the window. These switches are mounted upon a bracket 27* and are characterized in individual pairs according to their connection with the respective sashes 5, by the references 28, 29, and 30. An operating rod 31 is connected, as in Figure 6, to each of the switches 28 and 29 and extends upward flush with the facing in a suitable covered channel provided therefor, to where it engages a pivoted lug 32, two of which are required for each of the sashes, one for either side. The lugs 32 are substantially S-shaped as shown in detail in Figure 19, so as to increase the leverage thereof when the switches are operated. The inner free end of these lugs frictionally engage the tail of the latch 24, and since these lugs are held normally in operative engagement with the vertically situated shafts 6 by a leaf spring 33, shown in Figures 12 and 13 pressure against the tail of the latch obviously urges the latter inward against the resistance of these springs and releases the thread segment 25 of the lug from its engagement with the helix of the shaft 6.

It will be understood that each sash 5 is provided with a pair of switches, and as

exemplified in Figure 1, these switches are situated upon either side of the sash. For example, switches 28 control the upper sashes, switches 29 control the intermediate sashes, while the switches 30 control the bottom sashes. The intermediate switch 29 is not required to have an operating rod 31, since it is in alignment with its respective sash. It may be stated that these switches may be all dispensed with if desired, since their operativeness only extends to the selective actuation of the sashes, and only indirectly functions when the sashes 5 are raised simultaneously. In order to dispense with the switches, the interior periphery of the sleeve 20, shown in Figures 8 and 9 may be screw threaded and the latches 24 deleted from the structure.

The windows are of such compact construction as to enable them to be effectively installed in large dwellings, commercial buildings, hotels and the like and are especially valuable for office buildings, since the draft through the windows may be regulated to a nicety, and due to their construction, may effectually prevent blowing of papers, and entrance of rain. The frames in which the sashes are mounted may be constructed of wood, metal or other material applicable to the purpose.

Referring now particularly to the operation of the window and minor details of construction, the Figure 6 provides a comprehensible reference. If it should be desired to raise all of the sashes simultaneously, all of the switches 28, 29 and 30 are pressed upward. This action causes the rod 31 to pivot the lugs 32, thus urging them to the position shown in the upper position of Figure 6. The latches are thus independent of the lugs, and the spring 33 urges the latch toward the screw threaded shaft 6, whereby the thread segment 25 may engage therewith. The crank 17 is then applied to the squared shaft 16 and turned, thereby revolving the horizontal shaft 11 through gears 14 and 13, likewise imparting simultaneous rotation to the several vertical shafts 6. This movement causes the sleeves 20 and 22 to move toward one another to co-operatively move the arms 19, 21 and 23.

Prior to operating the sashes individually, it is necessary first to close them by reverse rotation of the crank 17, and assuming for example, it is desired to open only the top sashes; all of the switches, except 28, controlling the upper sash are pressed up, while 28 is pressed down. This action obviously holds the latches 24 out of engagement with the shafts 6 in the former case and effects engagement in the latter instance. The crank 17 is rotated as previously set forth.

It will be understood that the above described action applies equally to all of the

sashes individually or collectively, and it is understood that the number of sashes is not restricted to six, the number shown, and as many more may be used as deemed practical for the operation described.

Manifestly, the construction shown is capable of considerable variation, and such variation as is within the scope of the appended claims, is considered within the spirit of the present invention.

I claim:

1. A window of the character described in which is provided a plurality of vertical screw threaded shafts adapted to be rotated by a common horizontal shaft, and a plurality of swingable sashes operated thereby, means to effect independent control of said sashes when the shafts are operated, said means comprising collars freely movable on said shafts to which the sashes are connected by arms, a latch having thereon a thread segment engageable with the threads of said vertical shafts pivoted to said collars and normally urged to such engagement, and means to release such engagements selectively from a common point on said window.

2. A window of the character described in which is provided a plurality of vertical screw threaded shafts operated by a common horizontal shaft; and a series of swingable sashes operated thereby; means to provide for independent control of said sashes, said means comprising collars capable of unrestricted vertical movement on said shafts to which the sashes are pivotally connected by a series of arms; a latch having a threaded portion and pivoted to said collars, means to hold said threaded portion normally in engagement with the threads of

said shaft to cause co-ordinate movement of said collar, and means to manipulate said latches independently or collectively from a common point on said window.

3. A window of the character described, a plurality of threaded vertical shafts and a common operating shaft; a series of sashes operated thereby; means to effect independent control of said sashes, the means consisting of collars capable of free movement over the threads of said shafts and having recesses therein; latching means pivoted in said recesses, the latter having a threaded portion held normally in engagement with the threads of said shaft, and means operated from a common point on said window to overcome the resistance of said holding means to permit selective control of said collars and sashes with respect to their operating shafts.

4. A window of the character described, a plurality of threaded vertical shafts and a common operating shaft, a series of swingable sashes operated thereby; means to cause said operation, means to permit of selective control of said sashes with respect to the vertical shafts, said latter means including collars to which said sashes are pivotally connected by a series of arms, and having free movement over the threads of said shafts, latches pivoted to said collars having an integral threaded segment held normally enmesh with the threads of said vertical shafts, and means operable from a common position on said window to release said segments to enable selective ones of said sashes to be controlled individually.

In testimony whereof I affix my signature.

UUNO E. TUOMI.
